UNITED STATES PATENT OFFICE

MAX KRISSIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA

MULTIPLE-BOBBIN BRAIDING CARRIER

Application filed January 11, 1928. Serial No. 245,958.

My invention relates to multiple bobbin carriers for braiding machines, and more particularly to an improved mounting of the bobbins on the carrier, my main object being to increase the material capacity of such carrier without increasing its spread or diameter. Heretofore, in carriers having multiple bobbins, the latter have been invariably placed side by side, involving an enlargement of the race-track circle of the machine for their accommodation; such enlargement beyond a certain size being uneconomical and resulting in a limit to the capacity of each carrier either in the number of bobbins employed or 10 the material capacity of each bobbin, too small a supply in the several bobbins necessitating an uncommercially frequent stopping of the machine for replenishing.

With this main object in view my improvements comprise novel means of mounting the bobbins in superimposed relation or tiers, permitting the employment of an increased number, each having adequate supply of material, with little or no increase of the race- 25 way circle, enabling me to manufacture, in a commercially successful and economical manner, a variety of braids not heretofore possible, and particularly those of heavy individual strands.

With this main object outlined, and with others that will appear as the description progresses, my invention comprises the structure hereinafter fully set forth in connection with the accompanying drawings, the novel features thereof being pointed out in the appended claims.

Fig. 1 is a front elevation of a multiple bobbin braiding carrier embodying my invention as applied to a particular type of carrier, 40 parts being broken away or shown in section to more clearly disclose detail structure.

Figs. 2 and 3 are respectively corresponding side and plan views of the same.

Fig. 4 shows a modification of my invention.

The carrier indicated in the drawings is particularly adapted for use in the type of braiding machine more fully shown and described in the patent of Robert Carl Rahm, No. 1,182,036 dated May 9, 1916, but serves

to illustrate my invention in a preferred and successfully operative embodiment.

Referring to the drawings, 5 represents generally the race-way engaging foot portion of the carrier and 6 the bobbin supporting standard thereon, the latter, as shown, comprising three spaced apart and inverted U-shaped members 6^a, 6^b and 6^c, and a uniting top cross bar member 7, provided with a row of thread guide eyelets 8, four being shown, one for each of the four bobbins 9, 9 and 10, 10 herein employed.

These bobbins, which are of the horizontal spool type preferred for the carrier indicated, are mounted on standard 6 in a novel and improved manner designed for their operating in a minimum of space required for their travel about the race-way course of the machine, which latter may be comparatively small for the number of strands thus introduced. This novel mounting consists in placing spools 9, 9 side by side in one tier and superimposing spools 10, 10 in a second tier, preferably directly above the lower tier, such mounting utilizing four large spools 75 while occupying only the space heretofore required by two. Two or more additional spools of equal size might readily be added in a further superimposed tier or tiers without increasing the spread of the carrier or increase in the size of the race-way circle of the machine, thus greatly increasing the carrier capacity and the nature of the braid producible commercially therewith without any machine change.

In order that the bobbins thus mounted for economy of space may operate freely and independently as required, each bobbin is mounted as shown on a standard supported spindle 11 so as to freely rotate thereon and each is provided as shown with an independent tensioned brake control for the unwinding feed of its supply strand. The spindles 11 extend entirely across the standard 6, in two aligned lengths, as shown, with their inner ends supported in the central member 6^b and their outer ends engaging in apertures in the outer members 6^a and 6^c, said apertures being preferably closed by handled latch plates 14 pivoted to the stand-

ard so as to swing across said apertures as shown and prevent axial displacement of the spindles. These latches are maintained in aperture closing position, as shown, by attached springs 15, the tension of which I 5 preferably utilize also by attaching its opposite end to a brake shoe 16 to force said shoe into contact with the rim of its respective spool so to control the feed rotation of 10 the latter on its spindle. These brake-shoes may be conveniently pivotally supported on upper and lower transverse shafts 17 and 18, as shown, carried by the standard 6, and each brake shoe provided with an operating 15 arm 19 to the outer end of which is pivoted one end of a rod 20, projecting vertically therefrom with its opposite end slidably supported in a bearing lug 21 on standard 6. Adjacent each said lug on the respective rods, 20 and preferably normally projecting therefrom in the same plane, are four fixed arms 22 projecting in the path of four tension weights 23, so that contact with any arm by its respective weight will lift its rod 20 and through its operating arm 19 free said 25 brake by turning it on its pivot.

The four weights 23, as shown, are vertically slidable in guide ways formed in the opposing walls of the rear legs of U-shaped 30 members 6^a, 6^b and 6^c, and by two additional uprights 24, 24 carried by the foot portion 5, and each weight has a freely rotatable pulley 25 mounted on its top face by which it 35 is vertically lifted in its respective guide way. A row of four idler top pulley wheels 26, 26, 26, 26, are shown rotatably carried on a shaft 27 having bearings in the upper portion of said rear legs of members 6^a, 6^b, and 6^c, and also in the top ends of additional 40 upright 24, 24, which shaft maintains the latter in fixed upright positions. Two other idler guide pulleys 28, 28, are shown carried by a shaft 29 mounted in inwardly projected extensions 30 from the front legs of members 45 6^a, 6^b, and 6^c. The strands of material from the two lower bobbins 9, 9, in the particular embodiment of the drawings, pass over the respective idler guide pulleys 28, 28, to their respective top idler pulleys 26, 26, thence 50 around their respective weight pulleys 25 and thence through their respective thread guide eyelets 8, 8; while the strands from the upper bobbins 10, 10, pass respectively to their top 55 pulleys 26, 26, around their respective weight pulleys 25, 25 and thence to their respective eyelets 8, 8. With this arrangement it will be seen that the strand from each bobbin is 60 individually tensioned by its respective weights 23, the latter having equal movement in their guide ways before acting on rod arms 22 to free the brake shoes 16 in the control of unwinding feed rotation of the latter. Also the tension springs 15 connecting the brake shoes 16 and the handled latch 65 plates 14, insures proper tension only when

said latches are in aperture closing position protecting displacement of their bobbin spindles 11. The weights 23, upon break or exhaustion of supply of the bobbin carried strand, will fall to the foot portion 5, 70 in which position it may readily be made to act on a stop motion mechanism as frequently employed and well understood without further showing or description.

The foregoing description clearly sets forth my invention as applied to the particular carrier shown and successfully employed in commercial production; but my invention is equally applicable to other type of carriers to supply each with a multiple number of bobbins, either to increase their capacity for long uninterrupted runs as by uniting the end strand of one bobbin to the beginning strand of the next, or to provide a plurality of strands to be interwoven, or for other novel 75 effects as may be suggested or developed in practice. In Fig. 4 I have indicated a modification in which the foot portion 5^a carries a standard 6^a on which the superimposed spindles 11^a are inclined angularly to receive a "vertical" type bobbin; the essential common feature being the introduction of increased bobbin supply by superimposing the bobbins, instead of placing them side by side, so as to add additional supply without increased spread of the carrier or enlargement of the race way circle of the braiding machine.

In addition to the specific modification shown and above referred to, other modifications within the spirit of my invention may be readily devised, and I do not desire to limit myself to the constructions herein set forth in detail, but what I claim is:

1. A bobbin carrier having a race-way-engaging foot portion, a plurality of bobbin-supporting spindles mounted thereon in superimposed relation, with individual thread-tensioning and releasing means for each spindle supported bobbin, and separate thread-guide eyelets arranged in spaced relation to each other and to their respective bobbins so as to maintain a fixed separated arrangement of the bobbin threads extending beyond said eyelets.

2. A bobbin carrier having a race-way-engaging foot portion, a plurality of bobbin-supporting spindles mounted thereon in tiers, with individual thread-tensioning and releasing means for each spindle supported bobbin, and separate thread-guide eyelets arranged in spaced relation to each other and to their respective bobbins so as to maintain a fixed separated arrangement of the bobbin threads extending beyond said eyelets.

3. A bobbin carrier having a race-way-engaging foot portion, a standard thereon having a plurality of thread-guide eyelets, and a corresponding plurality of bobbin-supporting spindles mounted on said standard

in superimposed relation, with individual thread-tensioning and releasing means for each spindle supported bobbin, said eyelets being spaced from each other and from their respective bobbins so as to maintain a fixed separated arrangement of the bobbin threads extending beyond said eyelets.

4. A bobbin carrier having a race-way-engaging foot portion, a standard thereon having a horizontal row of thread-guide eyelets, a vertically projected row of tension-weight guide ways, and a plurality of bobbin-supporting spindles mounted on said standard in superimposed relation adjacent said guide ways and beneath said eyelets.

5. A bobbin carrier having a race-way-engaging foot portion, a plurality of spaced standards carried by said foot portion, a plurality of horizontally arranged bobbin-supporting spindles mounted in said standards in superimposed relation, and a plurality of vertically movable bobbin control tension weights guided between said standards.

6. A bobbin carrier having a race-way-engaging foot portion, a plurality of spaced standards carried by said foot portion, a plurality of horizontally arranged bobbin-supporting spindles mounted in said standards in superimposed relation, movable latch plates to lock said spindles in position, tension actuated control means for each spindle supported bobbin, and a latch connected tension spring acting only when said latch is in spindle locking position.

35 7. A bobbin carrier having a race-way-engaging foot portion, a plurality of spaced standards carried by said foot portion and having a uniting top bar provided with a plurality of thread-guide eyelets, a plurality of horizontally arranged bobbin-supporting spindles mounted in said standards in superimposed relation with movable latch plates to lock said spindles in position, a tension control brake for each spindle supported bobbin, tension springs for said brakes connected to said latch plates to hold the latter in spindle locking position, a plurality of vertically movable tension weights guided between said standards, and brake releasing means connecting each tension weight with its respective spindle supported bobbin.

8. A bobbin carrier having a race-way-engaging foot portion, a standard thereon having a row of thread guide eyelets and a corresponding row of tension weight guide ways, and a corresponding number of bobbin-supporting spindles mounted on said standard in superimposed relation, said eyelets being spaced from each other and from their respective bobbins so as to maintain a fixed separated arrangement of the bobbin threads extending beyond said eyelets.

In testimony whereof I affix my signature.
MAX KRISIEP.
